(57) **CLAIM**

The ornamental design for cassette with magnet, as shown and described.

DESCRIPTION

FIG. 1 is a top, front, right perspective view of a cassette with magnet showing our new design;

FIG. 2 is a top plan view thereof;

FIG. 3 is a bottom plan view thereof with a portion of the unclaimed subject matter removed to show the interior coil;

FIG. 4 is a left side view thereof;

FIG. 5 is a right side view thereof;

FIG. 6 is a front elevation view thereof;

FIG. 7 is rear elevation view thereof;

FIG. 8 is a top, front, right perspective view thereof in an alternate configuration with the magnet in a removed position;

FIG. 9 is a top plan view of the magnet;

FIG. 10 is a bottom plan view of the magnet;

FIG. 11 is a right side view of the magnet, with the left side view being a mirror image thereof;

FIG. 12 is a front elevation view of the magnet; and,

FIG. 13 is a rear elevation view of the magnet.

The uneven length broken lines illustrate the boundary of the claimed design, and form no part thereof. The even length broken lines shown in the drawings illustrate portions of the cassette with magnet that form no part of the claimed design. Contrast in materials in FIGS. 1-13 is shown using line shading on some surfaces and stippling shading on others.
